UNITED STATES PATENT OFFICE

CHESTER L. DAVIS, OF WASHINGTON, DISTRICT OF COLUMBIA, ASSIGNOR TO WIRED RADIO, INC., OF NEW YORK, N. Y., A CORPORATION OF DELAWARE

GLOW-DISCHARGE DEVICE

Application filed August 14, 1928. Serial No. 299,501.

My invention relates to glow-discharge devices in general and more specifically to glow-discharge devices employed in systems for the reception of signaling energy.

An object of my invention is to provide a glow-discharge device which may be employed in systems for the transmission and reception of signal impulses.

Another object of my invention is to provide a glow-discharge device which may be employed in the system of television reception of my invention described in my copending application Serial No. 300,979, filed August 21, 1928, entitled Signaling system.

Still another object of my invention is to provide a glow-discharge device having certain frequency characteristics.

A better understanding can be had of the glow-discharge device of my invention by referring to the specification following and to the accompanying drawings, wherein, Figure 1 is an illustration of one form of the glow-discharge device of my invention; Fig. 2 is an illustration showing the glow-discharge device of my invention; Fig. 3 shows another form of the glow-discharge device of my invention; Fig. 4 is an illustration showing a cross-section of the glow-discharge device of my invention and Fig. 5 is a graph which shows the operation of the glow-discharge device of my invention.

In systems for the transmission and reception of pictures, moving pictures and views, it has heretofore been the practice to employ elaborate arrangements and complicated apparatus to obtain satisfactory results. In my copending application Serial No. 300,979, filed August 21, 1928, a system for the reception of television signals is described. In this system, signal impulses of different frequency values correspond to the respective light and dark areas. Variations in the intensity of the light and dark areas is exhibited as variations in the intensity of the current of the respective frequency. In the receiving system of my invention, variations in frequency cause different areas of a glow-discharge device to be energized. Variations in the intensity of the current accompanying the respective frequencies

causes a corresponding variation in the intensity of the illuminated area in the glow-discharge device of my invention.

The glow-discharge device of my invention is illustrated in Fig. 1 of the accompanying drawings. The container 1 is constructed of any suitable material such as silicate composition or quartz. Container 1 may have a thin side wall or be designed as a condenser lens, or an enlarging lens to reflect the light as desired. The interior of the side wall may be ground in such a manner that the picture to be received will be easily discernible. A winding 2 is supported inside container 1. Winding 2 has frequency characteristics corresponding to the frequency characteristics of the transmitted light current variations or the complete band covered by the modulations of different frequency at the transmitting station, the minimum frequency of the transmitted light variations corresponding to the length of the winding 2. Container 1 is evacuated of air and filled with an inert gas such as neon or krypton. In the operation of the glow-discharge device of my invention the terminals 3 and 4 may be connected to the source of frequency variations and accompanying variations of energy. The minimum frequency value of winding 2 may correspond to approximately one half the wavelength of the minimum frequency transmitted. The energy distribution, represented as energy maximum and minimum response changes with the frequency. Assuming that terminal 3 is at a minimum value of energy at a given instant, the maximum energy may energize winding 2 at *m*. A decrease in the frequency of the source of supply would cause the energization of winding 2 at *n*. Further decreases in frequency would energize winding 2 at *O*, *P*, *Q*, and *R* respectively. Frequency values between these decreases would energize the winding 2 at intermediate points. The intensity of the energization exhibited as luminous radiation corresponds to the values of the energy accompanying the respective frequencies. The operation is similar to standing wave phenomena where current nodes and antinodes are exhibited

which move along the length of the conductor corresponding to changes in frequency of the source of exciting energy.

- 5 Figs. 2 and 3 show other forms of the glow-discharge device of my invention. In Fig. 2, the container 1a similar to container 1 of Fig. 1, encloses winding 2a which corresponds to winding 2 with the difference in respect to the plane in which the greater lengths of winding 2a is positioned. In Fig. 10 3 windings 2 and 2a are adjacent. Two individual containers 1 and 1a may be employed and positioned in such a manner that the greater lengths of one winding are in a 15 horizontal plane while corresponding lengths of the other windings are placed in the vertical plane. By such an arrangement it is possible to cause the energization of windings 2 and 2a and the area of luminous radiation 20 to be exactly and clearly defined. Fig. 4 of the accompanying drawings shows a cross-section of the glow-discharge device of my invention. In this illustration a slight modification is shown. Container 1 may be of 25 suitable glass, quartz, boro-silicate or other silicate composition. Windings 5 and 6 may be provided wherein the greater lengths of the windings lie in the vertical and horizontal planes respectively.
- 30 Fig. 5 is a graph which shows the operation of the glow-discharge device of my invention. The frequency is represented by the vertical line F. The frequency characteristics, or indirectly the length of the winding 35 C, is represented by the horizontal line. The area energized by the maximum energy value at a given instant is represented by the line "response". It is intended to show that the different points, along the length of the 40 winding where luminous radiation is exhibited, is a function of the frequency. A similar graph could represent the relation between the strength of the energy at each frequency response and the intensity of the 45 luminous radiation.
- 50 Many modifications of the glow-discharge device of my invention are possible without departing from the scope of my invention. A common electrode may be employed adjacent 55 to the windings of the glow discharge device. A metal plate could be employed adjacent to inductive winding 2 and the source of energy electrically connected to terminals 3 or 4 and the metal plate. Container 1 may be of a 60 boro-silicate composition, having the sides parallel to the greater lengths of winding 2, comprising a composition including an element or compound capable of conducting electrical energy. The glow-discharge device of 65 my invention having inherent frequency characteristics may be employed in suitable circuit arrangements comprising inductance and capacity or combinations thereof. In Fig. 5 of the accompanying drawings the numerical 70 values of F and C are arbitrary.

I realize that many modifications of the glow-discharge device of my invention are possible without departing from the scope of my invention and it is to be understood that my invention shall not be limited to the accompanying drawings but only as defined in the appended claims.

What I claim as new and desire to secure by Letters Patent of the United States is as follows:

75 1. A glow discharge device comprising a pair of screen like electrodes, each of said electrodes being constituted by an inductance member having the turns thereof disposed parallel one to the other the electrodes being disposed with the turns of one inductance member extending in a direction substantially normal to the turns of the other inductance member, and an envelope containing a luminously responsive gas enclosing said inductance members.

80 2. In a glow discharge device, a pair of inductance elements disposed in different parallel planes, one of said inductance elements including a multiplicity of turns having portions thereof extending parallel one to the other, the other of said inductance elements being constituted by similarly related turns with the turns of one inductance element extending in a direction different from the direction of the turns of the other inductance element, and having luminously responsive gas surrounding the turns of said inductance elements.

85 90 95 100 In testimony whereof I affix my signature. CHESTER L. DAVIS.
